BATHTUB

Isaac B. Gardiner, Trenton, N. J.

Application March 4, 1936, Serial No. 67,120

1 Claim. (Cl. 4—173)

This invention relates to new and useful improvements in bathtubs and the object of the invention is to provide a tub of such a construction as will promote safety and reduce to a minimum the possibility of injury as a result of slipping while standing in the tub.

The invention together with its objects and advantages will be best understood from a study of the following description taken in connection with the accompanying drawing wherein:

Figure 1 is a longitudinal sectional view through a tub embodying the features of the present invention.

Figure 2 is a fragmentary top plan view of the tub at one end of the latter.

Figure 3 is a sectional view through the tub.

Referring to the drawing by reference numerals it will be seen that the tub indicated generally by the reference numeral 5 is characterized by 20 having in the bottom thereof and for the greater portion of its length a raised section 6, extending from one end of the tub to a point inwardly from the relatively opposite end of the tub and a 25 smaller depressed section 7 extending from the terminus of the raised section 6 to the last named end of the tub.

The depressed section 7 of the tub is adapted

for use as a foot bath and is provided with the usual drain 8.

The raised section 6 is intended for use when taking a body bath or a shower and to promote safety the raised section 6 is provided in the top 5 thereof with a recess of slightly less length and width than the section 6 and fitted and secured in any suitable manner within this recess, and indicated by the reference numeral 9 is a mat 10 of rubber or other suitable material. At the 10 junction of the sections 6 and 7 there is provided a raised transverse rib 11 which intermediate its ends is provided with a drain slot 12 through which the water will drain from the mat 10 into the depressed end 7 of the tub to be 15 carried off through the drain 8.

Having thus described the invention, what is claimed as new is:

A bathtub having in the bottom thereof a raised portion extending from substantially one end of 20 the tub to a point materially inwardly from the relatively opposite end of the tub, said raised portion having a recess in the top face thereof, a mat fitting snugly within said recess, and a rib projecting upwardly from the raised bottom of 25 the tub and provided intermediate its end with a drain slot.

ISAAC B. GARDINER.
